UNITED STATES PATENT OFFICE.

FRANZ JOSEF FISCHER, OF DRESDEN, GERMANY, ASSIGNOR TO THE FIRM KOCH & STERZEL A. G., OF DRESDEN, GERMANY

TRANSFORMER.

Application filed January 27, 1925, Serial No. 5,078, and in Germany December 4, 1923.

There have been proposed various means for reducing the no-load losses of a transformer at light loads. In particular it is known, in connection with three-phase 5 transformers, with which the present invention is concerned, to change over from a delta-connected system used under full load conditions to a star-connected system at lighter loads, this conversion from delta- to 10 star-connected system, according to the arrangement proposed, being both primary sided and secondary sided, that is, both the primary windings and secondary windings being converted from delta to star connections. 15

In contradistinction therewith, in accordance with the invention, the primary windings are converted from delta connection at full load to star connection at light load, 20 while the secondary windings are always star-connected whether at full load or light load, the transformation ratio being maintained in such a manner that the subdivided secondary windings are connected in parallel at full load and are double-star-connected at light load.

This method has inter alia the advantage that, since a star connection of the secondary windings is always available, the star point 25 can be used as the neutral point and can always be fully loaded.

A further advantage of the method in accordance with the invention is that a transformer built for operation according thereto and connected for light loads may be connected in parallel with other transformers under full load.

As a further method of reducing the no-load losses with lightly-loaded transformers, the arrangement in series of otherwise parallelly-disposed secondary winding sections is known, but only in the form of double-star-connection in a certain sense. The known arrangement, however, has no 45 concern with a three-phase transformer and is not star- or double-star-connection.

The invention is diagrammatically illustrated in the accompanying drawing in which similar reference characters denote 50 corresponding parts and in which Figs. 1 and 2 show the delta connections of the pri-

mary coils; Figs. 3 and 4 show the star connections of the primary coils; Figs. 5 and 6 show the star-connected subdivided secondary coils in which the sections are connected in parallel; Figs. 7 and 8 show the star-connected subdivided secondary coils in which the different sections are connected in series or double-star, and Fig. 9 illustrates the adjustable switch in the position 55 for full load.

Referring first to Figs. 1-4, U, V and W are the receiving ends of the primary coils and X, Y and Z the corresponding opposite ends thereof. If U be connected with Z, V 60 with X and W with Y, the primary coils are delta-connected for full load, as indicated in Fig. 2. If X, Y and Z of the primary coils be connected together, then the delta connection is changed to star connection 65 for low load, as shown in Figs. 3 and 4.

Referring now to Figs. 5-8, the receiving ends of some of the sections of the secondary coils are u , v , w and the opposite ends thereof x , y , z , and the starting ends of the other sections of the coils are u' , v' , w' and their corresponding opposite ends x' , y' , z' . If now u be connected with u' , v with v' and w with w' , x with x' , y with y' , z with z' , and x' , y' and z' are connected together, as 70 shown in Fig. 5, the two sections of the secondary coils on each leg are star-connected for full load, as shown in Fig. 6, the star point O being used as the neutral point. If, on the other hand, u' be connected with v' and w' , x with y' , y with z' and z with x' , the one section of a secondary coil on one leg is connected in series with another section of the secondary coil on another leg. This connection used for low load is 75 termed "double-star-connection," the same being indicated in Fig. 8.

The adjustable switch shown in Fig. 9 illustrates the method of operation.

As shown, on the common spindle 1, are 80 mounted double or multiple contact knives 2', 2'', for the primary system, and 3', 3'', for the secondary system, the contacts 4 of the primary system and 5 of the secondary system being arranged opposite one another 85 in series, in such manner that on rotation of the spindle through 180° the change over

from the connections for full-load condition (indicated in Fig. 9) to those for low-load condition is effected.

What I claim is:—

- 5 A method of reducing the no-load losses on three-phase transformers having the secondary winding subdivided in sections continuously star-connected, consisting in

changing the primary windings from delta connections at full load to star connections at low load and simultaneously changing the secondary windings from parallel at full load to series or double-star at low load.

In testimony whereof I affix my signature.

FRANZ JOSEF FISCHER.
